United States Patent Office

Des. 188,455
Patented July 26, 1960

188,455

BUILDING

Ernest Kump, 26184 Arastradero Road, Los Altos, Calif.

Filed July 19, 1957, Ser. No. 47,006

Term of patent 14 years

(Cl. D13—1)

FIG. 1

The side and end not shown on the drawing are substantially like the side and end shown.

I claim:

The ornamental design for a building, as shown and described.
